(57) **CLAIM**

The ornamental design for a bottle, as shown and described.

DESCRIPTION

FIG. 1 is a top perspective view of a bottle, showing my new design;

FIG. 2 is a front elevation view thereof;

FIG. 3 is a right side elevation view thereof;

FIG. 4 is a top plan view thereof;

FIG. 5 is a bottom plan view thereof;

FIG. 6 top perspective view of a modified embodiment of the design shown in FIGS. 1 through 5; and,

FIG. 7 is a front elevation view thereof.

The broken dot-dash lines in FIG. 5 define the bounds of the claim and form no part thereof. The dotted broken lines in FIGS. 1-7 illustrate portions of the design that form no part of the claim.
